(57) **CLAIM**

The ornamental design for a game, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of the game, showing the flattened box top with foldable sides, shown separately for ease of illustration;

FIG. 2 is a top plan view of the game board;

FIG. 3 is a top plan view of a set of playing cards; and,
FIG. 4 is a bottom plan view of a playing card, each of the
playing cards in the set having the same back.

1 Claim, 4 Drawing Sheets
